Herbert S. Chase, Flushing, N. Y., assignor to Bernard Cahn Co., Inc., New York, N. Y.

Application July 9, 1954, Serial No. 31,351

Term of patent 7 years

(Cl. D87—3)

To all whom it may concern:

Be it known that I, Herbert S. Chase, a citizen of the United States of America, residing in Flushing, New York, county of Queens, and State of New York, have invented a new, original, and ornamental Design for a Wallet, of which the following is a specification, reference being had to the accompanying drawing, forming part thereof, wherein:

Figure 4 is an inner perspective view of same in open position, and

I claim:

The ornamental design for a wallet, substantially as shown.
